UNITED STATES PATENT OFFICE.

MORRIS LERNER, OF CHELSEA, MASSACHUSETTS, ASSIGNOR TO A. L. SMITH IRON WORKS, OF CHELSEA, MASSACHUSETTS, A CORPORATION OF MASSACHUSETTS.

STAIR STRUCTURE.

Application filed September 26, 1925. Serial No. 58,817.

This invention pertains to stair structures and more particularly to structures of that type in which forms made of sheet material, for example, sheet steel, and each comprising a tread and a riser portion, are assembled to make the stair structure, the sheet metal tread portions of the forms usually supporting treads proper consisting of concrete, wood, rubber or the like which are clamped to or interlocked with the form.

Commonly the tread and riser portion of the form are integrally united at the rear angle of the stair and adjacent forms are attached to one another by bolts, rivets or the like at the forward angle or nosing of the stair.

In order to provide a suitable pocket or receptacle for the concrete filler or other tread proper of the stair, it is customary to extend the upper part of the riser above the level of the tread of the next higher form so as to provide what may be termed a "nosing flange," but while the desired receptacle for the concrete tread is thus provided, the upwardly extending nosing flange of the riser is a constant source of annoyance and danger since it is very difficult to anchor it rigidly in position and as soon as the concrete begins to wear, this upwardly projecting nosing flange is exposed, constituting a menace to the safety of the user. Since this nosing portion is subject to rapid wear it is desirable that it may be replaced readily, but in the usual construction such replacement of the nosing portion or the attachment of a wear plate at this point is extremely difficult since the space immediately to the rear of the nosing is completely filled with concrete which cannot easily be drilled and which will not hold screw threads.

The riser supports the load applied to the rear part of the next tread below and the connections uniting it to the next tread above are thus called upon to sustain this load. Since in the usual construction these connections are relatively few in number the riser frequently pulls away from the tread next above to such an extent as to elevate the nosing flange of the riser above the level of the concrete surface and to produce cracks in the concrete adjacent to the nosing.

Moreover, with usual constructions two or more workmen are required to assemble the stair forms and in some arrangements various auxiliary arrangements in addition to

the tread and risers must be prepared, carried in stock by the manufacturer, and handled by the workmen in assembling the stair.

The principal object of the present invention is to provide a stair structure having great strength and durability and in which the nosing of the stair is unusually strong and wear resistant, provides additional stiffness to the stair structure as a whole, and is capable of ready renewal when worn; to provide a structure wherein the tread and riser are integrally united at the nosing so that the tread and riser cannot separate at this point; to provide a structure wherein ample provision is made for interlocking the concrete or other tread proper with the metal parts and wherein wear of the concrete will not expose dangerously sharp portions of the metal sub-structure; to provide a structure of such character as to permit ready assemblage of the parts by a single workman; and to provide a form having a riser of great strength, considering the material employed and which is adapted to form a sanitary angle with the treads next below.

In the accompanying drawings in which a preferred embodiment of the invention is illustrated, by way of example:

Fig. 1 is a longitudinal sectional view of a portion of a staircase embodying this invention;

Fig. 2 is a section on the line 2—2 of Fig. 1;

Fig. 3 is a perspective view of a portion of one of the improved stair forms;

Fig. 4 is a view similar to Fig. 1 showing a modification of the invention;

Fig. 5 is a section on the line 5—5 of Fig. 4;

Fig. 6 is a view similar to Fig. 1 showing still another modification of the invention; and

Fig. 7 is a fragmentary vertical section to large scale showing the application of a wear plate to the nosing.

Referring now to the drawings in detail, 1 denotes stringers consisting of channels to which are bolted or otherwise fastened angle irons or carriers 2. These angle irons form the immediate supporting means for the stair forms 3.

Each form 3 comprises a riser portion 4 and a tread portion 5 integral therewith. At the juncture of the riser and tread 1 provide a nosing 7 of substantially U or channel

shape. This nosing rises appreciably above the level of the tread and the rear wall 8 of the nosing preferably inclines downwardly and forwardly so that the nosing and tread 5 meet in an acute angle. The rear edge portion 9 of the tread is bent upwardly and forwardly to form an angle, preferably acute, with the main body of the tread. The lower portion of the riser is bent forwardly at 10 to provide the usual sanitary construction, and then rearwardly at 11 in a plane substantially parallel with the part 9 of the tread. Below the part 11 the riser is bent to extend forwardly as shown at 12 to form a flange 15 substantially parallel with the tread 5.

The parts 5 and 12 are provided with openings 13 and 14 respectively and in assembling the two forms, flange 12 of one form is placed upon tread 5 of the other, and parts 9 and 11 are brought into juxtaposition with the holes 13 and 14 aligned. A bolt or other fastening means passes through each pair of these holes and also through the angle iron 2 supporting the tread.

When the forms are assembled, concrete 15 is placed upon the treads. The parts 8 of the nosing and 11 of the riser together with the tread form a pocket or mould trapezoidal in front to rear section for the reception of the concrete, and the concrete when set is locked in place by reason of the upward convergence of parts 8 and 11. As will be seen in Fig. 1, the rearward slope of part 10 provides an obtuse angle between the concrete surface and the riser and this makes for increased sanitation since the stairs are easier to clean and there are no cracks for the dirt to collect in.

The arrangement thus far described provides a stair whose metal parts are integrally connected at the nosing so that there is no possibility of their pulling away from each other with consequent exposure of edges which may be dangerous to the user, while at the same time furnishing a maximum strength at the point where it is most desired. Moreover since the flange 9 of the tread is disposed at the rear side of the lower part 11 of the next riser, the latter is locked in position so that it cannot be driven rearwardly by the impact of the feet of the user and the stair is greatly strengthened in a front to rear direction by this hook-like interengagement of the parts. Moreover, the shape of the stair form is such that the concrete tread is firmly locked in position, while the double angle at the lower part of the riser furnishes great strength in a transverse direction.

The provision of the hollow channel-like nosing has a further advantage in addition to those which have heretofore been mentioned. As illustrated in Fig. 7 a wear plate 30 may be secured to the top surface 65 of the nosing when the nosing becomes

worn through long use. This wear plate 70 may readily be secured in position by means of screws 31 passing down through threaded holes drilled in the upper member 7 of the nosing. As the chamber 32 within the nosing is empty it is an easy matter to drill these holes and to tap them for the reception of the screws, whereas if the nosing overlay the concrete tread such drilling and tapping would 75 be a difficult and unsatisfactory operation. The wear plate 30 may, as shown, cover merely the top edge of the nosing or may have an extension upon its front edge overlapping the upper part of the riser.

Figs. 4 and 5 illustrate a novel form of angle iron which facilitates the assembly of the stairs. This angle iron 16 is notched in its upper or horizontal flange and the metal from these notches is bent perpendicular to the horizontal flange of the angle to form locking lugs 17 preferably of wedge-like form. These lugs are apertured as at 18 to receive locking wedge pins 19. The lugs 17 pass up through the holes 13 and 14 in the assembled stair forms 3 and the wedge pins 19 are inserted in the apertures 18 to lock the forms to the angle irons and to each other.

The great advantage in this type of angle iron lies in the fact that it requires but one man to assemble the stairs whereas in the construction shown in Figs. 1 to 3, it requires two men, one to manipulate the bolt and another the nut. With this improved angle iron all that is necessary is to align the holes with the locking lugs and insert the wedge pins.

In Figs. 4 and 6 are shown two slightly modified types of stair forms. In both of these modifications the bent-up portion 9 of the tread, as hereinbefore described, is eliminated, the tread terminating in a horizontal plane. In Fig. 4 the rear of the tread is slightly elevated as at 20 so that the horizontal portion 12' of the riser may be received between the tread and the corresponding angle iron or carrier 2^a. In Fig. 6 the rear end of the carrier or angle iron 2^b is depressed as at 21 so as to receive the horizontal portion 12'' of the riser between it and the tread. In both of these modifications the tread is supported upon the riser. It will be observed that by eliminating the portion 9 a saving in material is effected without a sacrifice of strength. While the lugs 18 are herein shown as integral with the angle iron, they may obviously be made as separate elements and suitably secured to the angles.

I claim:

1. A stair structure comprising a riser, a nosing of double thickness, a tread portion integral with the riser, said nosing extending upwardly above the tread portion and having its rear wall inclined forwardly 130

and downwardly and the lower portion of the riser being inclined backwardly and downwardly whereby a cementitious filler 5 poured upon the tread portion will tend to be locked in place by the rear wall of the nosing.

2. In a stair structure, a plurality of stair forms each comprising a substantially channel-shaped nosing, and a riser and tread 10 integral therewith, the rear wall of said nosing inclining forwardly and downwardly, the riser having a substantially horizontal flange at its lower part and a forwardly and upwardly inclined portion adjacent to said 15 flange, whereby when said stair forms are assembled, the tread and forwardly inclined wall of the nosing of one form together with the forwardly inclined portion of the riser of the form next above provide a pocket for 20 the reception of a plastic filler, said pocket positively locking said filler to the first named form.

3. In a stair structure, stringers, carriers 25 fastened to said stringers, and stair forms each comprising a tread and a riser, each

riser having a forwardly directed flange at its lower edge, each tread being supported upon a carrier and having its rear margin slightly elevated to provide a space between 30 said tread and its carrier for the reception of the forwardly directed flange on the riser.

4. In a stair structure, a carrier comprising an angle iron having upstanding lugs on one of its flanges, said lugs being provided with apertures for the reception of locking 35 pins.

5. A stair structure comprising a carrier having a horizontal supporting member, a lug projecting upwardly from said supporting member, said lug being a transverse 40 aperture, a pair of stair forms, each form having a part resting upon said supporting member, said parts having aligned apertures for the passage of the lug, and a wedge pin passing through the aperture in 45 the lug and thereby locking the forms to the carrier.

Signed by me at Boston, Massachusetts,
this 24th day of September, 1925.

MORRIS LERNER.
